UNITED STATES PATENT OFFICE.

CHARLES B. NAMIOC, OF NEW YORK, N. Y.

GARTER.

Application filed August 24, 1925. Serial No. 51,911.

This invention relates to garters. More particularly, this invention is directed to a novel article of manufacture such as a garter having a beaded trimming of improved construction and to the method of making same.

An object of the invention is to provide an improved method of applying a beaded ornamentation or trimming to an extensible body such as a garter.

Another object of the invention is to provide a garter with an ornamental trimming of the character described comprising few and simple parts, which is neat and artistic in appearance to a high degree, and relatively inexpensive to manufacture.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view of a beaded garter embodying the invention;

Fig. 2 is a cross-sectional view taken on line 2—2 in Fig. 1;

Fig. 3 is a fragmentary view of a stretched body portion of the garter with the beads applied thereto; and

Fig. 4 is a perspective view showing one method of applying the beads.

Referring in detail to the drawing, 10 denotes a garter embodying the invention having a body portion 10^a comprising a back strip 11, an overlying front layer 12, both of which are shirred, an elastic member 13 interposed between the two, and longitudinally extending rows of stitches 14 for securing said strip, layer and member together as shown in Figs. 1 and 2.

Said strip and layer may be made of ribbons of silk or satin, or of other suitable fabric and the strip 11 is preferably formed of wider material than the layer 12 so that the edge portion 11^a of the strip forms a ruching border for the layer. The body portion 10^a of the garter as described above may be hand or machine made in any manner well known in the art.

A dominant feature of the invention is the

application of beaded trimming or ornaments to the garter. In the form shown in the drawing, suitable beads 15 such as artificial pearls, or the like, are strung preferably singly on a non-elastic thread or string 16 and with the aid of a needle 17, each bead is stitched individually to the front layer 12 to conform with a desired artistic design D. (See Figs. 1 and 3.)

One method of applying the beads 15 is to stitch all the beads from a single thread 16 to the front layer 12 to conform with the design D leaving one of the ends of the thread 16 unanchored, then to stretch the body portion 10^a to its practical maximum limit, next to allow said body portion to return to its normal length, and thereafter to permanently anchor the free end of the thread to the body portion. The step of stretching of the body portion before finally anchoring the thread in the method as described above is effective to provide a little slack thread between each bead after the body portion is returned to its retracted position. Thus the extension of the body portion is in no way interfered with by the unstretchable property of the thread and injury to the beaded ornamentation is avoided since the said slack eliminates the possibility of breakage of the thread when the garter is stretched on putting it on or taking off.

In Fig. 4 is shown a second method embodying the invention for applying the beaded ornamentation. Here each section of the body portion to which a bead is fastened is stretched over the operator's fingers when stitching the bead to the front layer of the body portion. Thus a little slack thread is provided between adjacent beads when the body portion is in its normally retracted position as in the case described above.

Still another method of providing slack thread between the beads consists of stretching the body portion over a form, stitching the beads in position to the front layer, and then permitting the body portion to return to its normal retracted position, thereby providing a little slack thread between the beads as described above.

After the thread has been permanently attached to the body portion, the garter may be finished by securing the ends together in any well known manner.

It will thus be seen that there is provided a device in which the several objects of this invention are achieved, and which is well

adapted to meet the conditions of practical use.

As various possible embodiment might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. An article of manufacture comprising a garter having a body portion formed to include an elastic member interposed between a shirred backing strip and front layer and a trimming consisting of a thread, and beads strung on the thread, said beads being secured to the front layer, said thread having a slack portion between adjacent beads to permit unrestricted extension of the body portion.

2. An article of manufacture comprising a garter having a body portion formed with a backing strip, an overlying front layer, both strip and layer being shirred, and an elastic member interposed between said strip and layer, and an ornamented trimming consisting of strung beads individually secured to said layer and slack fastening means for said beads to permit unrestricted extension of the body portion.

3. In an article of manufacture, an extensible body portion having a shirred outer layer, and an ornamental trimming comprising a thread and beads strung on the thread and stitched to said layer, said thread having slack portions between the beads to permit unrestricted extension of the body portion.

4. In an article of manufacture, the combination of an elongated extensible body portion having a shirred outer layer of relatively non-elastic material, and a trimming comprising beads strung on a thread and secured to extend along said layer, said thread having a slack portion between adjacent beads to permit unrestricted longitudinal stretch of said body.

5. In an article of manufacture, the combination of an elongated extensible body portion having a shirred outer layer of relatively non-elastic material, and a trimming comprising beads strung on a thread and secured to extend along said layer, said thread being non-elastic and having slack portions to permit unrestricted longitudinal stretch of said body portion.

6. A garter comprising an elastic webbing of annular form, covering fabric members of annular form attached to said webbing along the longitudinal edges of the latter, said covering members being each of a length exceeding the normal inexpanded length of said webbing and provided with transversely extending folds when said elastic webbing is in its normal inexpanded state, and an endless row of beads fastened by a thread to the outer one of said covering fabric members, said thread being passed alternately through the last-mentioned covering member and a bead in the series, the length of each portion of the thread between adjacent bead elements being longer than the distance between adjacent bead elements when the garter is in its normal inexpanded state.

7. An article of manufacture comprising a garter having an elongated extensible body portion, a single thread, and beads strung on said thread secured to the body portion, said thread having a slack portion between adjacent beads to permit unrestricted extension of the body portion.

In testimony whereof I affix my signature.

CHARLES B. NAMIOT.
